UNITED STATES PATENT OFFICE.

LOUIS R. LEMOINE, OF PHILADELPHIA, PENNSYLVANIA, ASSIGNOR TO UNITED STATES CAST IRON PIPE & FOUNDRY COMPANY, OF BURLINGTON, NEW JERSEY, A CORPORATION OF NEW JERSEY.

TURN-TABLE.

1,282,885.

Specification of Letters Patent.

Patented Oct. 29, 1918.

Application filed April 18, 1918. Serial No. 229,263.

To all whom it may concern:

Be it known that I, LOUIS R. LEMOINE, a citizen of the United States, and a resident of the city and county of Philadelphia and State of Pennsylvania, have invented 5 certain new and useful Improvements in Turn-Tables, of which the following is a true and exact description, reference being had to the accompanying drawings, which 10 for a part thereof.

My present invention relates to the construction of turntables, and particularly the turntables of pipe molding plants where 15 relatively heavy loads are carried at the periphery of the turntable. In a pipe molding turntable of the character referred to, these heavy loads consist of the molding flasks supported either at the periphery or 20 on outriggers of the table located at a distance radially beyond the circular supporting track which surrounds the center of the table. In turntables of this construction, the framework comprises radial beams framed into radial girders supported on the 25 circular girders located directly above the circular track and connected at the center to a casting. The radial beams in effect form levers which fulcrum on the circular girders, thus tending to bend or raise the 30 center of the turntable under the influence of the heavy flasks carried either at the periphery or on the outriggers of the turntable.

The object of the present invention is to 35 provide a simple and effective turntable construction, in which means are provided for resisting this tendency of the radial members of the turntable to tilt upward at the central portion of the turntable without requiring intricate construction and large, and 40 otherwise unnecessary amount of material needed to make the turntable itself stiff enough to reduce this tendency.

This I accomplish by utilizing the central column about which the table turns as a 45 means for impressing a downwardly acting force on the inner ends of the radial turntable beams. In practice this column is anchored at its base to the massive foundation beneath the turntable and a thrust bearing, 50 preferably a ball or roller bearing, is interposed between this column and the turntable. Ordinarily this column supports crane arms, or other overhead parts, so that the weight 55 of the column and the parts supported by it is ample to resist the upward dishing tend-

ency of the turntable. When the weight of the column, and parts supported by it, is insufficient for this purpose, the dishing tendency is restrained in whole or in part by the tension to which the lower portion of the 60 column is then subjected through its anchor connection to the foundation.

The various features of novelty which characterize my invention are pointed out with particularity in the claims annexed to 65 and forming a part of this specification. For a better understanding of the invention, however, and the advantages possessed by it reference may be had to the accompanying drawings and descriptive matter in which 70 I have illustrated and described preferred embodiments of my invention.

Of the drawings:

Figure 1 is an elevation with parts broken away and in section of a portion of a pipe 75 molding plant.

Fig. 2 is a sectional elevation of a portion of the turntable construction shown in Fig. 1 taken on a larger scale.

Fig. 3 is a plan view on a smaller scale of 80 a portion of the turntable.

In the drawings, A represents the turntable proper, which turns about a central post or column K, and is provided between its center and periphery with a curved rail 85 A' resting upon the tops of roller supports B running on a curved stationery track rail C surrounding the post K. The rolls B are journaled in the usual manner on the ends of radial shafts B', secured at their inner ends 90 to a ring B''. The latter surrounds and is journaled on a base member K' forming a part of the lower central step bearing I for the turntable. The ring B'' and parts connected thereto revolve about the axis of the 95 post K with half the angular velocity of the turntable A when the latter is rotated. The outer ends of the shafts B' pass through the usual circular spacing rings B'.

The turntable, as shown, is formed of deep 100 radial trussed beam elements D, comprising top and bottom girder members connected by suitable vertical and inclined members D'. The inner ends of the main girder elements of the trussed beams D are riveted to 105 radial flanges H' secured to a cylindrical body or casting H and forming the central or end portion of the turntable. The radial beams are framed into circular girders D' and adjacent radial beams D are connected 110

by cross bars D². Flasks supporting radial beams E are secured between each adjacent pair of main radial beams D. The flasks F are shown as double vertical pipe mold 5 flasks arranged at each side thereof at regular intervals around the periphery of the turntable, and are supported between the adjacent beams E and between each beam D and beams E. The central step bearing I, carried by the supporting member K¹ is engaged by the lower end of the cylindrical body H.

A thrust bearing J comprising anti friction balls J' is interposed between the upper 15 end of the turntable central or hub member H, and a flange or abutment K² carried by the column or post K. The latter is shown as connected at its upper end in the roof truss members L of the building inclosing 20 the turntable, and is shown as carrying the inner ends of the angularly adjustable crane arms M and N, the outer ends of which are supported by the stationary track P carried by the truss members L. The lower end of 25 the post or column K is connected to the foundation in the construction shown by anchor bolts K³.

With the construction described all, or the major portion, of the weight of the column 30 K and the load carried thereby is transmitted to the cylindrical central member H of the turntable through the thrust bearing J. The portion, if any, of this weight not balanced by the peripheral portion of the turntable, including the flasks F, is transmitted 35 to the step bearing I. In case the central column K supports no overhead parts, or the weight of the column and parts supported by it is insufficient, the anchor bolts K³ connecting the column K to the foundation for 40 the turntable put the lower portion of the column under sufficient tension to hold the center of the turntable against upward movement.

45 The described construction gives ample strength and rigidity with the use of much less material than would be required to give the turntable the necessary stiffness to resist its tendency to dish upward under the influence of the weights of the flasks F, than would be required if the column K was not used to hold down the center of the turntable, and this advantage is obtained without any accompanying disadvantages.

50 While in accordance with the provisions of the statutes I have illustrated and described the best form of my invention now known to me, it will be apparent to those skilled in the art that changes may be made

in the form of my invention without departing from its spirit, and that some features of my invention may sometimes be used to advantage without a corresponding use of other features of the invention.

Having now described my invention, what 65 I claim as new and desire to secure by Letters Patent, is:

1. In a pipe molding plant the combination with a turntable and supporting means therefor comprising a central support on 70 which the table is journaled and a circular track surrounding said central support, a series of flasks supported by said table at the outer side of said circular track and a thrust bearing between said support and said table 75 opposing the tendency of the table to dish under the influence of the weight of the flasks.

2. In a pipe molding plant the combination of a turntable, a central support upon 80 which the table is journaled, a circular supporting track surrounding said central support and upon which said table bears, a series of flasks carried by said table beyond the said supporting track, a vertical post rising 85 above said central support, overhead parts supported by said post above the table, and a thrust bearing through which the weight of said post and overhead parts supported by it is impressed on the table at the center 90 of the latter.

3. In a pipe molding plant the combination of a turntable comprising radial beam members, a central support upon which the table is journaled, a circular supporting 95 track surrounding said central support, a series of flasks carried by said table beam members beyond the said supporting track, a vertical post rising above said central support, and a thrust bearing between said post 100 and table through which the tendency of the inner ends of said beams to rise is opposed.

4. In a pipe molding plant the combination of a turntable comprising radial beam members, a central support upon which the 105 table is journaled, a step bearing which resists downward movement of the center of the table, a circular supporting track surrounding said central support, a series of flasks carried by said table beam members 110 beyond the said supporting track, a vertical post rising above said central support, crane arms mounted on said post above the table, and a thrust bearing through which the weight of said post and crane arms is transmitted to the inner ends of said beams.

LOUIS R. LEMOINE.
